UNITED STATES PATENT OFFICE.

WOLF COHEN, OF FORT WORTH, TEXAS.

OIL-TANK PROTECTOR.

1,270,497.

Specification of Letters Patent. Patented June 25, 1918.

Application filed January 19, 1915. Serial No. 3,160.

To all whom it may concern:

Be it known that I, WOLF COHEN, a citizen of the United States, residing at Fort Worth, in the county of Tarrant, State of Texas, have invented certain new and useful Improvements in Oil-Tank Protectors; and I do hereby declare the following to be a full, clear, and exact description of the invention, such as will enable others skilled in the art to which it appertains to make and use the same.

This invention relates to oil tank protectors.

The object of the invention resides in the provision of a simple device which may be readily associated with an ordinary oil tank and will protect the latter against destruction from lightning.

It is well known that it is the gas escaping from oil tanks that is ignited by lightning. The object of this invention is to provide a means for carrying away all gas that escapes from openings in the tanks and to carry the gas far enough away to prevent any ignition near the tank and a series of tanks can all be connected to the same pipe for carrying away the gas. The principal object is to keep all gas away from the exterior of the oil tanks so that there can be nothing to cause fire.

In describing the invention in detail reference will be had to the accompanying drawings wherein like characters of reference denote corresponding parts in the several views, and in which—

Figure 1 is a top view of an oil tank having the invention associated therewith;

Fig. 2, a side view of same;

Fig. 3, a section on the line 3—3 of Fig. 1, and

Fig. 4, a section on the line 4—4 of Fig. 2.

Referring to the drawings 10 indicates an oil tank having an opening 11 in the top thereof. Mounted upon the tank and covering the opening 11 is a box or hood A which includes a rubber cover B. The box A is formed of an interior wood portion 12 and an exterior rubber portion 13. A pipe 14 is supported above the top of the tank 50 inwardly of the edge of the latter and has one end passed through the wall of the hood A and then through the portion 12 and extended downwardly through the opening 11 into the interior of the tank. The terminal 55 of this end of the pipe 14 has secured there-

to a bell 15 for directing gas into the pipe. The end of the pipe 14 remote from the bell 15 is directed laterally as at 16 and then carried downwardly in spaced relation to the side of the tank into the ground and 60 connected with a suitable conduit for conveying the gas to desired points. It will thus be seen that the pipe 14 is insulated from the tank and lightning that would ordinarily strike the tank and destroy same 65 will be caught by the pipe 14 and harmlessly conveyed to the ground.

All openings about the upper part of an oil tank should be protected with the hood A. This hood is shown in two parts. It is 70 apparent that this hood can be made in a single piece and it may be preferable to construct this hood in a single piece and of material that will be a non-conductor of electricity.

The object in curving the pipe 14 about the top of the tank is to bring the pipe or a considerable portion of the pipe close to the top of the tank which is always very warm and may be said to be hot. This will serve 80 to heat the gas in the pipe and expand the same so that the gas will be driven off more rapidly and thus create a suction within the tank and thus take away the gas more rapidly.

The invention is useful for oil tanks, railway tank cars and for protecting the lives of workmen in mines. Any opening where gas may escape can be protected and the gas can be collected and carried away. The 90 gas can thus be collected and used for heating and other purposes.

What is claimed is:—

1. The combination with an oil tank having an opening in its top, a hood of insulating material covering and hermetically sealing said opening, a gas conveying pipe disposed above the top of the tank and bent concentrically with the latter and insulated throughout its length from said tank, one end of said pipe being carried through the hood and extended downwardly within the tank, a bell secured to the last named end of the pipe, and the other end of said pipe being directed laterally and then downwardly in spaced relation to the side of the tank and embedded in the earth at its lower end.

2. Means for protecting oil tanks from lightning comprising a hood of non-con-

ducting material for securely closing any opening about the tank and a pipe extending from within the tank for collecting gas and extending out through said hood and coiled about the tank in spaced relation thereto to be heated thereby for expanding the gas therein and for carrying away the gas from the tank, said pipe being insulated throughout its length from said tank and

the lower end thereof being embedded in the earth.

In testimony whereof I affix my signature in the presence of two witnesses.

WOLF COHEN.
